United States Patent Office

E. H. ASHCROFT, OF LYNN, MASSACHUSETTS.

Letters Patent No. 72,585, dated December 24, 1867.

IMPROVED APPARATUS FOR WASHING SHEEP-SKINS.

The Schedule referred to in these Letters Patent and making part of the same.

TO ALL WHOM IT MAY CONCERN:

Be it known that I, E. H. ASHCROFT, of the city of Lynn, in the county of Essex, and State of Massachusetts, have invented a new and improved Apparatus for Washing Sheep-Skins with the wool on; and I do hereby declare that the following is a full and exact description thereof, reference being had to the accompanying drawings, and to the letters of reference marked thereon, like parts being represented by like letters in the several figures.

The nature of my invention consists in washing sheep-skins having the wool on, by machinery, to be hereafter described, by which the skins can be better washed than by hand, as usual. Great economy of labor is effected, and the skin or pelt is rendered much more flexible or pliable.

To enable others skilled in the art to make and use my invention, I will proceed to describe its construction and operation. In the drawings—

Figure 1 represents a side view of a revolving hollow wheel, A, having several apartments *a* made by radial divisions *b*, which have perforations *c*. This wheel is constructed on a central shaft, B, and can be revolved in any suitable manner, such as a belt, or by means of water acting on buckets *d*. This wheel is supported by and revolves inside of a semicircular or other suitably-shaped tub *e*, which has perforations *e* in its bottom and sides.

Figure 2 represents a transverse vertical section of wheel and tub.

Figure 3, a vertical longitudinal section of same; and

Figure 4 a side elevation of tub.

The wheel A has several perforations in its side, as seen at *f* and *g*, the former for the purpose of putting the skins through into the apartments of the wheel, and the latter for the introduction of water into said apartments by means of a pipe.

The operation is as follows: After the skins have been soaked a certain time, they are put into the several apartments of the wheel, and water introduced into the same, as said above, and the wheel then made to revolve. As it revolves, the skin drops from one radial division or partition to the next one of the same apartment, which cleanses it of dirt, at the same time rendering the skin more flexible by a kind of slapping operation. The wheel is revolved until the skins are well washed. The dirty water runs out continually through the holes in the radial partitions, and the circular slots near the periphery of the wheel, and finally escapes through the perforations in bottom and sides of tub.

The skins may also be washed and "broken" by a wheel with rigid or flexible buckets, and as it turns in the semicircular tub, this being a modification of the process first described, the water to be supplied in any convenient way.

Having thus described my invention, what I claim as new, and desire to secure by Letters Patent of the United States, is—

An apparatus for washing sheep-skins with the wool on, constructed and operated in the manner substantially as shown and described.

E. H. ASHCROFT.
